SHEET FEEDING MECHANISM FOR
PRINTING PRESSESWilliam K. Eckhard, Westerly, R. I., assignor to
C. B. Cottrell & Sons Company, Westerly, R. I.,
a corporation of Delaware

Application October 11, 1939, Serial No. 298,999

5 Claims. (Cl. 271—46)

My invention is directed to improvements in so called lap or streamline sheet feeders in which the sheets are fed in lapped relation.

My invention is more particularly directed to feeders of the above type which are adapted to feed in proper register lapped sheets in runs of varying lengths, within predetermined limits.

The object of my invention is to increase production and to obtain improved quality in register 10 of sheets of different length by providing a sheet feeder and a sheet slow-down device for forwarding varying length sheets in lapped relation to a front sheet register guide; means being employed for adjusting both the speed of travel of 15 both the sheet feeder and the sheet slow-down device.

A practical embodiment of my invention is represented in the accompanying drawings, in which

Fig. 1 represents a diagrammatic view showing 20 the relative positions of sheets of a maximum length when the leading sheet is in a selected position on the impression cylinder;

Fig. 2 represents a similar view when the leading sheet is in a second position;

Fig. 3 represents a similar view when the leading sheet is in a third position;

Fig. 4 represents a similar view showing the relative positions of sheets of a minimum length when the leading sheet is in a selected position 30 on the impression cylinder;

Fig. 5 represents a similar view when the leading sheet is in a second position;

Fig. 6 represents a similar view when the leading sheet is in a third position;

Fig. 7 represents a detail side view partly in section of my improved sheet feeder with the parts in the positions they assume when the maximum length sheets occupy the position shown in Fig. 1;

Fig. 8 represents a similar view with the parts in the positions they assume when the maximum length sheets occupy the positions shown in Fig. 2;

Fig. 9 represents a detail view with the parts in the positions they assume when the sheets 45 occupy the positions shown in Fig. 3; and

Fig. 10 represents the adjusted position on the crank disc of the cam connecting rod for controlling the speed of the sheet slow-down device when used in connection with the minimum length sheets.

The front sheet register guide 1 is mounted on the rock shaft 2 in position to be swung by the usual means, not shown herein, into and out of 55 position to engage the advance edges of succe-

sive sheets as they are fed in lapped relation over the fixed sheet support 3 by the sheet feeder 4, which feeder in the present instance is shown as an endless tape carrier. This endless tape carrier may be driven at the desired speed according to the length of sheets being fed, by a change speed drive of well known or approved form, through a belt 5 which passes at one end around a pulley 6 on the endless carrier shaft 7 and at its other end around a pulley 8 on the variable speed shaft 9 of the change speed device. This shaft 9 may be driven from the shaft 10 of the change speed device through the usual belt 11 and divided pulleys 12 and 13. The usual hand wheel 14 may be provided for manually adjusting the effective diameters of the divided pulleys 12 and 13 to vary the speed of the shaft 9, belt 5 and endless tape carrier 4 according to the length of sheets to be fed. The shaft 10 of the change speed device may be driven at a constant speed from the rotary crank shaft 15 through the belt 16 and pulleys 17 and 17*.

Means are provided for slowing down the feeding of sheets to a greater or lesser extent according to their length so that the longer or shorter sheets, as the case may be, will be brought to a substantial stop as their advance edges reach the front register guide 1. This adjustable slow-down device is herein shown as comprising the following elements: the spring pressed slow-down hooks 18 (one only of which is shown) are hinged as usual to a carriage 19 at each side of the feeder, which carriage is reciprocated just below the fixed sheet support 3. These slow-down hooks 18 are yieldingly held at the limit of their upward movement in the path of the advancing lapped sheets by a spring 20 on each carriage 19. The usual hook swinging roller 21 travels around the track 22 as the carriage is reciprocated, to bring the hooks into and out of the path of the advancing sheets as the carriage moves forward and backward respectively.

A rod 23 connects the carriage 19 to one arm 24 of a rock lever carried by the rock shaft 25; the other arm 26 of which lever carries a roller 27 which is operated by the inclined surface of a cam 28 slidably mounted on a fixed bar 29.

This cam 28 is connected to one end of a rod 30, the other end of which rod is adjustably connected to a crank disc 31 carried on the rotary shaft 15. This connection of the rod 30 with the crank disc 31 may be adjusted toward and away from the shaft 15 to vary the throw of the cam 28 and thereby the speed of the slow-down hooks 18 according to the length of sheets being 55

fed; it being understood that the throw of the connecting rod 30 is decreased for a shorter sheet and increased for a longer sheet. The crank disc 31 rotates once for each sheet being fed. In 5 Figs. 7 and 8 the connection between the rod 30 and the crank disc 31 is shown as adjusted outwardly for the maximum length sheets while in Fig. 10 the connection is shown as adjusted inwardly for a minimum length sheet.

10 The rotary impression cylinder is denoted by 32 and its sheet grippers by 33. The rotary sheet transfer carrier is denoted by 34 and its grippers by 35. These grippers 35 are arranged to take the head of the registered fed-in sheet 15 from the front register guide 1 and to present it to the impression cylinder grippers 33.

The longer sheets illustrated in Figs. 1, 2 and 3 are denoted by A, B, C, D and the corresponding shorter sheets illustrated in Figs. 4, 5 and 6 are 20 denoted by A', B', C', D'.

It will be noted that when the parts are in the position shown in Fig. 1 or 4 the longer sheet A or the shorter sheet A', as the case may be, is engaged by the impression cylinder grippers 33 25 and the tail of the sheet is just clearing the head of sheet B or B' which is just contacting the slow-down hooks 18. Sheets C or C' and D or D' are being conveyed in a lapped relation by the feeder to the press. In Fig. 2 or 5 the sheet A or A' advancing at cylinder speed shows more 30 clearness between the sheets A or A' and B or B' which has just reached the front register guides 1. The overlap between the sheets B or B' and C or C' is increased due to retarding 35 speed of sheet B or B' in the slow-down hooks 18. Sheets C or C' and D or D' run at uniform speed with overlap remaining the same. In Fig. 3 or 6 the sheet A or A' is still advancing at cylinder speed. The grippers 35 on the rotary transfer carrier 34 are just taking the sheet B or B' 40 with the front sheet guides 1 just starting to move to the position shown in Fig. 1 or 4. The overlap between sheets B or B' and C or C' has increased while sheet B or B' remain at the 45 front register guide 1 during the side guiding period. The sheets C or C' and D or D' run at uniform speed with lap remaining the same.

From the above description it will be seen that by regulating the speed of the feeder and the 50 speed of the slow-down device proportional to the length of the sheets being fed-in to the press, sheet lengths within the capacity of the press may be delivered to the front register guides with positive control and in proper timed relation so as not to interfere with side guiding or other functioning mechanism and with no interference between the tail of a preceding sheet with the advance edge of the next succeeding sheet.

It is evident that this feeding mechanism can 55 be applied to both under-fed and over-fed machines with equal advantage.

It is evident that various changes may be re-

sorted to in the construction, form and arrangement of the several parts without departing from the spirit and scope of my invention, and hence I do not intend to be limited to the particular embodiment herein shown and described, but what I claim is:

1. In a sheet fed rotary printing press, a front sheet register guide, a device for forwarding lapped sheets of different lengths thereto, a sheet slow-down device adjacent the front sheet register guide, and manually controlled means for varying the speed of travel of both the sheet forwarding device and the sheet slow-down device according to the length of the sheets being fed. 15

2. In a sheet fed rotary printing press, a front sheet register guide, a traveling endless carrier for forwarding lapped sheets of different lengths thereto, a sheet slow-down device adjacent the front sheet register guide, and manually controlled means for varying the speed of travel of both the endless carrier and the sheet slow-down device according to the length of the sheets being fed. 20

3. In a sheet fed rotary printing press, a front sheet register guide, a traveling endless carrier for forwarding lapped sheets of different lengths thereto, a sheet slow-down device adjacent the front sheet register guide, and manually controlled means for varying the speed of travel of both the endless carrier and the sheet slow-down device according to the length of the sheets being fed, said means including a change speed device operatively connected to the endless carrier. 25

4. In a sheet fed rotary printing press, a front sheet register guide, a traveling endless carrier for forwarding lapped sheets of different lengths thereto, a sheet slow-down device, and manually controlled means for varying the speed of travel of both the endless carrier and the sheet slow-down device according to the length of the sheets being fed, said means including a change speed device operatively connected to the endless carrier and a rotary crank of adjustable throw for operating the slow-down device. 35

5. In a sheet fed rotary printing press, a front sheet register guide, a traveling endless carrier for forwarding lapped sheets of different lengths thereto, a sheet slow-down device comprising a reciprocating carriage, sheet engaging hooks carried thereby, a rock lever connected to the carriage, a cam for operating the rock lever and a rotary crank for operating the cam, and manually controlled means for varying the speed of travel of both the endless carrier and the sheet slow-down device according to the length of the sheets being fed, said means including a change speed device operatively connected to the endless carrier and means for varying the throw of the rotary crank. 40

WILLIAM K. ECKHARD.
